UNITED STATES PATENT OFFICE.

ELDA G. SMITH, OF SYRACUSE, NEW YORK, ASSIGNOR TO CROUSE-HINDS COMPANY, OF SYRACUSE, NEW YORK, A CORPORATION OF NEW YORK.

DESIGN FOR AN ELECTRICAL-CONDUIT OUTLET-BOX.

48,331.

Specification for Design.

Patented Dec. 21, 1915.

Application filed September 15, 1915. Serial No. 50,901. Term of patent 14 years.

To all whom it may concern:

Be it known that I, ELDA G. SMITH, a citizen of the United States, residing at Syracuse, in the county of Onondaga and State of New York, have invented a new, original, and ornamental Design for Electrical-Conduit Outlet-Boxes, of which the following is a specification, reference being had to the accompanying drawing, forming a part hereof.

In the drawing, Figures 1 and 2 are, respectively, a plan and side elevation of this conduit outlet box; and Fig. 3 is an end elevation looking to the right in Fig. 2.

This new design for a conduit outlet box presents in plan the appearance of a disk *a*, and a bar *b* extending radially across the face of the disk and terminating at one end at the center of the disk, and having its other end extended beyond the periphery of the

disk, and presents in side elevation the appearance of a right angular figure having a long horizontal arm and a short vertical arm *c* rising from the center of the disk *a*, and a part *c'* beneath the disk, which gives the impression that the arm *c* extends through the disk.

What I claim is:—

The ornamental design for an electrical conduit outlet box substantially as shown and described.

In testimony whereof, I have hereunto signed my name, in the presence of two attesting witnesses, at Syracuse, in the county of Onondaga and State of New York, this 12th day of August, 1915.

ELDA G. SMITH.
